(57) **CLAIM**

The ornamental design for a game console gamepad thumbstick cover, as shown and described.

DESCRIPTION

FIG. 1 is a first perspective view of a game console gamepad thumbstick cover showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded perspective view thereof; and,

FIG. 10 is another perspective view thereof, shown in an environment of use.

The broken lines shown in FIGS. 2 and 9 illustrate portions of the game console gamepad thumbstick cover that form no part of the claimed design. The broken lines shown in FIG. 10 are environment, that form no part of the claimed design.
